UNITED STATES PATENT OFFICE.

JAMES INGELLS, OF MUSKEGON, MICHIGAN.

DESIGN FOR A TABLE-PEDESTAL.

45,876.

Specification for Design.

Patented June 2, 1914.

Application filed February 16, 1914. Serial No. 819,116. Term of patent 7 years.

To all whom it may concern:

Be it known that I, JAMES INGELLS, a citizen of the United States, residing at Muskegon, in the county of Muskegon and State of Michigan, have invented a certain new, original, and ornamental Design for Table-Pedestals, of which the following is a specification, reference being had to the accompanying drawing, forming a part hereof.

In the accompanying drawing Figure 1 is an elevation, and Fig. 2 is a plan of the pedestal, both of these figures being deemed

necessary to give a clear impression of the design desired to be covered, namely, a pedestal column.

I claim:

The ornamental design for a table pedestal, as shown.

Signed at Muskegon Michigan February 7, 1914.

JAMES INGELLS.
